VAPOR GENERATOR

Johann Költing, Duisburg, Germany, assignor to
The Babcock & Wilcox Company, Newark,
N. J., a corporation of New Jersey

Application November 14, 1935, Serial No. 49,738
In Germany May 26, 1934

7 Claims. (Cl. 122—302)

This invention has to do with vapor generating apparatus, and more particularly to boilers of the water tube type.

An object of this invention is to provide vapor generating apparatus wherein improved means is provided for supporting cross-tube baffles which serve to direct the flow of heating gas through the boiler tubes.

A further object is to provide an improved form of boiler slag screen.

The above and other objects will be apparent from an examination of the following description and claims, when taken in connection with the accompanying drawings, in which:

Fig. 1 is a vertical section somewhat diagrammatic in character, and illustrating the invention as applied to one form of two drum vertical tube boiler;

Fig. 2 is a diagrammatic view illustrating the spacing arrangement of the tubes, the view being taken on the line 2—2 of Fig. 1;

Fig. 3 is a view similar to Fig. 1 and illustrating a modified form of the invention;

Fig. 4 is a view similar to Fig. 1 and illustrating one manner of applying the invention to a four drum boiler of the bent tube type;

Fig. 5 is a view similar to Fig. 4 and illustrating a modified form of the application of the invention to a four drum bent tube boiler;

Fig. 6 is also similar to Fig. 4 and illustrates a further modified form;

Fig. 7 is a diagram illustrating the spacing of the tubes in the modification shown in Fig. 6, the view being taken on the line 7—7 of Fig. 6; and

Fig. 8 is a view similar to Fig. 7 and taken on the line 8—8 of Fig. 6.

According to one specific embodiment of the invention, there is provided a vapor generating apparatus which comprises means defining a chamber for the combustion of fuel, an upper steam and water drum, a lower water or mud drum, a group of tubes connecting the drums and arranged in rows extending both longitudinally and transversely of the drums and across the heating gas outlet of the combustion chamber, and a separate row of tubes also connecting the drums and being spaced apart a greater distance than the spacing of the first named tubes and being offset with respect to the transverse rows of the first named tubes. The tubes forming the separate row are disposed for a portion of their length at the combustion chamber side of the first-named tubes to provide a boiler slag screen for retarding the deposit of slag on the

first-named tubes, and are disposed for another portion of their length between and transversely of the first-named tubes. A cross-tube baffle is also provided and is supported by that portion of the separate row of tubes which extends between the first named tubes.

Referring now in detail to the construction illustrated and particularly to the construction shown in Fig. 1, it will be observed that there is represented a two-drum vertical tube boiler consisting of a boiler-drum 1, a mud-drum 2, a riser tube group 3, a downcomer tube group 4, and a superheater 5. The boiler is disposed above a combustion chamber 10 and the tube group 3 is disposed across the upper and outlet side of the combustion chamber. Behind the tube group 3, the tubes of which are in line, there is located a tube row 6 of twice the pitch, offset by half the pitch. These tubes are passed across the tube group 3 and carry the baffle wall 7. In the tube group 3 and carry the baffle wall 7. In their upper part, they are located in front of the tube group 3.

Fig. 2 shows the tube arrangement along the section 2—2 of Fig. 1. The tubes of the tube group 3 may be replaced individually in the well-known manner through the tube lanes which have been left free. At the upper part, the tubes 6 cross the tube group 3 a second time and carry the roof 8. The discharge end of tubes 6 may be located by means of lengthening tubes in the steam space of the boiler-drum 1.

In Fig. 3, a different way of arranging the tubes 6 is represented; first they are located ahead of the tube group 3, then cross the latter and carry the baffle wall 7, so as to be located on the other side in front of the group. The tubes 6 may discharge below the roof 8 into the water space of the boiler-drum and may be lengthened, if necessary, up to the steam space by means of extension tubes, or they may pass through the roof 8, cross the tube group 3 another time, and may discharge directly into the steam space of the boiler-drum 1.

Referring to the modification shown in Fig. 4, it will be observed that the invention is shown as being applied to a four drum bent tube boiler which comprises three upper drums 20, 21, and 22 connected to a lower drum 23 by tubes 24, the latter being suitably divided into groups 26, 27, 28, 29 and 30. A superheater 31 may be disposed between groups of tubes 26 and 27. The tubes 24 of the group 26 are arranged in rows extending both longitudinally and transversely of the drums, as in the previously described modification, and a separate row of tubes 32 connect

the steam space of the drum 20 with the water drum 23 and are arranged for a portion of their length at the side of the group 26 which is nearest the combustion chamber 33. The lower 5 portions of the tubes 32 extend transversely of and between the tubes 24 of the group 26 and thence downwardly and connect into the drum 23. A cross-tube baffle 34 is supported by the portions of the tubes 32 which extend transversely 10 of the group 26. The tubes 32 are preferably of wider spacing longitudinally of the drum than the tubes 24 of group 26. The tubes 32, in their position forward of the group 26 in the upper portion of the furnace, provide a slag screen arrangement which is similar to that shown in Fig. 2. This arrangement of widely spaced tubes forward of a group of closely spaced tubes is effective as a slag screen, when slag forming fuel is used, because the tubes provide for the quenching 15 of molten slag and are spaced apart a sufficient distance that any slag adhering thereto will not easily bridge the spaces between tubes.

Referring to Fig. 5 of the drawings it will be observed that the invention is shown as applied 20 to a four drum boiler of the bent-tube type, wherein cross-tube baffles 40 and 41 and a longitudinal baffle 42 are arranged to provide flow paths for the heating gases from the combustion chamber 43 generally transverse of the boiler 25 tubes, instead of generally parallel to the boiler tubes as described in Fig. 4. The boiler comprises upper drums 44, 45 and 46 and a lower drum 47 and the drums are connected by means of tubes 48 divided into groups 50, 51, 52, 53 and 30 54. The cross-tube baffle 40 is supported by a row of tubes 55 which connects the rear upper drum 46 with the lower drum 47. These tubes 35 55 extend between the tubes 48 in the manner described in connection with the previous modifications. The lower ends of tubes 55 are curved so as to extend parallel to the tubes 48 forming the group 50, but are not in transverse alignment with the tubes of group 50. The longitudinal baffle 42 is supported by the lower portions 40 of the row of tubes 55 and merges at its upper end into the cross-tube baffle 40. The cross-tube baffle 41 is supported by a row of tubes 56 which also connect the rear drum 46 and lower drum 47. The baffle 41 provides with the baffle 40 a 45 return gas pass 57 across the boiler tubes 48. The upper vertical portions of tubes 55 and 56 are in alignment, and are offset with respect to the tubes 48 to permit their passing transversely between the latter. The lower ends of the tubes 55 50 are curved and extend downwardly and parallel to the lower ends of the tubes 55 and are connected into the drum 47.

In Figs. 6, 7 and 8 of the drawings there is 55 illustrated a further modification of my invention as applied to a four drum bent tube boiler. The upper drums are indicated by the reference characters 60, 61 and 62, and the lower mud drum by the reference character 63. The drums are connected by a plurality of steam generating tubes 64 divided into groups 65, 66, 67, 68 and 69. Longitudinal baffles 70 and 71, and cross-tube baffles 72 and 73 provide transverse gas passes 74, 75, and 76, respectively. A row of tubes 77 are connected at the lower end thereof 60 to the mud drum 63 and extend upwardly in front of the group of tubes 65. The tubes 77 are offset with respect to the tubes of the group 65 and alternate tubes 77a of this row are bent 65 so as to extend transversely of the tubes of the groups 65, 66 and 67 and are connected at their 70

upper end to the middle drum 61. The cross-tube baffle 72 is supported by the transversely extending portion of the tubes 77a. The remaining alternate tubes 77b of the row 77 continue upwardly in front of the group 65 and 5 connect into the front drum 60 to provide a boiler slag screen. The longitudinal baffle 70 is supported by one row of the tubes 64 of the group 65. A second row of tubes 79 connects the mud drum 63 with the rear upper drum 62 and also 10 extends transversely of and between the tubes 64 of the groups 66, 67, 68 and 69 for supporting the cross-tube baffle 73, the longitudinal baffle 71 being supported by tubes 64 of the rear group 69. 15

I claim:—

1. In vapor generating apparatus, the combination of means providing a chamber for the combustion of fuel, an upper drum, a lower drum, a group of vapor generating tubes connecting the drums and extending across the outlet side of said chamber, other tubes connected at corresponding ends to one of the drums and arranged in a row extending longitudinally of such drum, the tubes of said row being disposed for parts of their lengths at the combustion 20 chamber side of the group of first-named tubes and substantially parallel to lower parts thereof for protecting the latter, and extending for parts of their lengths transversely of and between groups of first-named tubes and connected to the 25 other drum at points behind those tubes of the group which are nearest the combustion chamber, the tubes forming the row being spaced apart a greater distance than the distance between the tubes forming the group. 30

2. In vapor generating apparatus, the combination of means providing a chamber for the combustion of fuel, an upper drum, a lower drum, a group of vapor generating tubes connecting the drums and extending across the outlet side of said chamber, other tubes connected at one of their ends to the lower drum at the side nearest the combustion chamber and extending upwardly and at the combustion chamber side of said group for a part of their length and then 40 transversely of the group and upwardly and connected at their upper ends to the upper drum, and a baffle supported by that portion of said last named tubes which extends across the group. 45

3. In a steam boiler, a furnace, spaced upper 50 drums, a lower drum, spaced front and rear banks of tubes separately connecting the upper drums to the lower drum and constituting the main steam generating surface of the boiler, baffle tubes connected to the lower drum alongside the front 55 bank and having their upper ends connected to an upper drum near the tubes of another bank, said baffle tubes having their intermediate parts extending transversely of at least two of said banks, a baffle supported by said intermediate 60 parts and extending across the tubes of said banks to direct the furnace gases transversely of said banks of tubes in a single gas pass, said baffle tubes having their lower parts located forwardly 65 of the tubes of the front bank so as to have a slag screen effect. 70

4. In vapor generating apparatus, the combination of means providing a furnace combustion chamber, front and rear upper drums, a lower drum, a plurality of separate banks of vapor 75 generating tubes separately connecting the upper drums with the lower drum and extending transversely of the path of the furnace gases, said banks constituting the main vapor generating surface of the boilers, baffle tubes communicat- 75

ing with the lower drum and extending upwardly at the combustion chamber side of said banks for substantial parts of their lengths to act as slag screen tubes and then transversely of one of said banks, and a baffle supported by the transversely extending portions of the baffle tubes, said baffle tubes being connected at their upper ends to the rear upper drum.

5. In a steam boiler, a furnace, an upper drum, a lower drum, spaced banks of tubes connecting said drums and constituting the main steam generating surface of the boiler, a superheater between said banks, other tubes connected to the lower drum alongside one bank and having their upper ends connected to the upper drum near the tubes of another bank, said other tubes having their intermediate parts extending transversely of one of said banks and between groups of the tubes in that bank, a baffle supported by 10 said intermediate parts to direct the furnace gases transversely of the first of said banks of tubes and then transversely of the superheater in a single gas pass, said baffle extending across the tubes of one of said banks.

15 6. In vapor generating apparatus, the combination of means providing a furnace combustion chamber, front and rear upper drums, a lower drum, a plurality of separate banks of vapor generating tubes separately connecting the upper drums with the lower drum and extending

transversely of the path of the furnace gases, said banks of tubes constituting the main vapor generating surface of the boiler, baffle tubes communicating with the lower drum and extending upwardly at one side of said banks for substantial parts of their lengths and then transversely of one of said banks, a baffle supported by the transversely extending portions of the baffle tubes and separating first and second gas passes, said baffle tubes being connected at their upper ends to the rear upper drum, and other baffle tubes connected to the lower drum and extending across a bank of tubes and supporting a baffle separating a second and third gas pass.

10 7. A bent tube boiler having a plurality of upper drums, means forming a lower submerged water chamber, front and rear banks of tubes connecting the upper drums to the lower submerged water chamber, sets of baffle supporting tubes connecting said water chamber with the upper drums, one set of said baffle supporting tubes having portions extending alongside and in front of said front bank of tubes to constitute a slag screen, said sets of baffle supporting tubes having transversely bent parts positioned between adjacent rows of the tubes of said banks, and baffle forming means carried by said transversely bent parts.

15 20 25 JOHANN KÖLLING. 30
